UNITED STATES PATENT OFFICE.

WILLIAM H. HARTMAN OF PHILADELPHIA, PENNSYLVANIA, AND GEORGE W. BORTON, OF HADDONFIELD, NEW JERSEY, ASSIGNEES TO PENNSYLVANIA CRUSHER COMPANY, OF PHILADELPHIA, PENNSYLVANIA, A CORPORATION OF NEW YORK.

CAGE-ADJUSTING MECHANISM FOR CRUSHER-MACHINES.

1,361,054.

Specification of Letters Patent. Patented Dec. 7, 1920.

Application filed June 9, 1919. Serial No. 302,874.

To all whom it may concern:

Be it known that we, WILLIAM H. HARTMAN and GEORGE W. BORTON, citizens of the United States, residing, respectively, at 5 Philadelphia, county of Philadelphia, and State of Pennsylvania, and Haddonfield, county of Camden, and State of New Jersey, have invented new and useful Improvements in Cage-Adjusting Mechanism for 10 Crusher-Machines, of which the following is a specification.

This invention relates to improvements in crushing and pulverizing machines designed, chiefly, though not exclusively, for 15 the crushing of coal, and in the accompanying drawing a machine suitable for that use is illustrated by way of example.

In a prior patent to Joseph L. Hiller, No. 1,020,501, March 19, 1912, is shown a crushing and pulverizing machine of the type to which in the accompanying drawings we have shown our invention applied. In the above mentioned patent is disclosed a crusher provided with a casing having 25 therein a rotary beater element inclosed by a pivoted cage; the cage being adjustable through a rack secured to its free end and meshing with a rack wheel upon a manually rotatable shaft.

30 This invention has for its object to provide an improved means for positively adjusting the pivoted grinding cage of such machines with relation to the hammers. It has been found that when these machines are used, there is a tendency for dirt and other matter to collect in the adjusting mechanism of the cage, particularly on and between the teeth of the rack and pinion resulting in difficulty in adjusting the cage 35 to the consequent wear of the hammers and the screen plates of the cage.

The above mentioned defects we have overcome by using an open faced rack provided with roller teeth, the rotation of 45 which prevents dirt from remaining for any considerable time upon the rack and also tends to brush from the rack wheel or pinion any dust which might have collected thereon. In order to further guard against 50 the above mentioned formation of dust in the adjusting mechanism, we use, instead of the ordinary type of rack wheel or pin-

ion, an improved type of wheel having a plurality of spaced, parallel series of teeth extending around its periphery. 55

The above and other features and objects of our invention will become obvious as the description proceeds.

In the accompanying drawings:

Figure 1 is a partial, vertical sectional view showing a crusher machine with our improved adjusting mechanism attached thereto;

Fig. 2 is a horizontal sectional view of the adjusting mechanism taken on line 2—2 65 of Fig. 1;

Fig. 3 is an elevational view of a detail of the mechanism, a portion of the rack being shown in vertical section.

Fig. 4 is a detail view taken at right 70 angles to the view shown in Fig. 3 and showing more clearly the means for securing the rack to the cage.

Referring to the drawings more in detail, 75 1 indicates the casing of the machine which may be of any desired form, and in which is located the hammer carrying shaft 2 having the disk 3 keyed thereto, said disk being provided at suitable intervals with the usual hammers 4.

80 The above mentioned shaft, disk, and hammers constitute the beater elements of the crusher, and the same are inclosed in a cage 5 pivoted at one end (not shown) to the casing 1 and having attached to its free end an adjusting rack 7, said rack being vertically reciprocated through a toothed sprocket 8 keyed to the shaft 9. The shaft 9 is manually rotated through the reducing gears 10, 11, the latter gear being located on 90 the shaft 12 provided with a hand wheel 13.

95 So much of the machine as we have above generally described is old and well known in the art, and is clearly disclosed and shown in the patent above referred to. As stated our invention resides in the improved type 100 of rack 7, sprocket 8, and the means for attaching the rack to the free end of the pivoted cage 5. As shown in the drawings the rack consists of two spaced parallel members 14, 15, joined at suitable intervals by studs 16 having rotatable sleeves 17 thereon. These studs together with their sleeves constitute the teeth of the rack, which teeth are

adapted to mesh with the rack wheel or sprocket 8. The sleeves 17 upon engagement with the sprocket 8 tend to rotate and hence any dirt which has collected upon the sleeves 5 falls away, the rotation of the sleeves also tending to brush away the dirt from the sprocket teeth. The sprocket 8 is shown as formed of three spaced parallel series of teeth 8^a, 8^b, and 8^c, but while we have shown 10 the sprocket as having three series of teeth, it is to be understood that the number of the series may be varied as desired. By employing a sprocket having spaced series of teeth openings are provided between the series through which dirt and foreign matter 15 may make its exit as will be quite clear from inspection of Fig. 2. It will be observed from an inspection of Fig. 2, that the side members 14, 15, of the rack have a bearing 20 upon lateral extensions 8^d of the sprocket hub and the rack is thus guided in its reciprocation.

The rack is held in engagement with its wheel and further guided in its reciprocation by means of a guide member surrounding the shaft 9 and formed from two substantially triangular plates 18, 19, joined together at their apices and at their base corners by studs 20 having thereon rotatable 25 sleeves 21. Those sleeves at the base ride on the side members 14, 15, of the rack when the latter is reciprocated and hold the rack in engagement with the sprocket 8.

In order to secure the rack to the cage 30 there is attached to the lower end of the rack between its side members 14, 15, a substantially triangular saddle member 22 (Figs. 3 and 4) adapted to rest at its base edge on a stud 23 located on the cage. The saddle 35 member is held upon the stud by means of a substantially semi-circular clamping member 24, formed from two plates 25, 26, held in spaced relation by suitable cross-members 27. The plates are each provided with 40 perforated ears 28 adapted to receive between them the corners of the saddle 22 and to be held in this position by suitable means such as the stud 29 passing through the ears and saddle and held therein by cotter pins 30.

50 The mode of operation of the crusher herein described is well known in the art and is clearly described in the patent to Hiller, above mentioned. From the above description it should be clear that we have devised 55 a structure which is a marked improvement over prior devices of the character disclosed in the Hiller patent, as crushers of this type when provided with our improved adjusting mechanism are less liable to become clogged

with dirt and as a result the cage may at all 60 times be easily manipulated.

While we have shown our improved adjusting mechanism as applied to a particular type of crusher it is to be understood that it may be used with other types in which similar adjustment is desired and that such modifications may be made therein as come within the scope of the following claims.

Having thus described our invention, what we claim is:

70 1. In a crushing and pulverizing machine, the combination with a pivoted grinding cage of a beater element therein, an open faced, roller toothed rack connected to the free end of said cage, a rack wheel having a 75 series of teeth adapted to mesh with said rack, and having clearance spaces on each side of said series of teeth between the same and the sides of the rack for the clearance of obstructing material, and means for operating the rack wheel to positively move the rack for adjustment of the cage.

2. In a crushing and pulverizing machine, the combination with a pivoted grinding cage, of a beater element therein, an open faced rack connected to the free end of said cage, a rack wheel having a plurality of 80 spaced parallel series of teeth in mesh with said rack, and means for operating the rack wheel to positively move the rack for adjustment of the cage.

3. In a crushing and pulverizing machine, the combination with a pivoted grinding cage, of a beater element therein, a roller toothed rack connected to the free end of 85 said cage, a rack wheel having a plurality of spaced parallel series of teeth in mesh with said rack, and means for operating the rack wheel to positively move the rack for adjustment of the cage.

90 4. In a crushing and pulverizing machine, the combination with a pivoted grinding cage, of a beater element therein, an open faced, roller toothed rack connected to the free end of said cage, a rack wheel having a 95 plurality of spaced parallel series of teeth in mesh with said rack, and means for operating the rack wheel to positively move the rack for adjustment of the cage.

100 4. In a crushing and pulverizing machine, the combination with a pivoted grinding cage, of a beater element therein, an open faced, roller toothed rack connected to the free end of said cage, a rack wheel having a 105 plurality of spaced parallel series of teeth in mesh with said rack, and means for operating the rack wheel to positively move the rack for adjustment of the cage.

110 In testimony whereof, we have hereunto set our hands in presence of two subscribing witnesses.

WILLIAM H. HARTMAN.
GEORGE W. BORTON.
